FUEL INJECTION PUMP

Everett M. Purdy, New Canaan, Conn., assignor to
 Eisemann Magneto Corporation, New York,
 N. Y., a corporation of New York

Original application November 7, 1935, Serial No.
 48,744. Divided and this application January
 18, 1938, Serial No. 185,587

12 Claims. (Cl. 103—41)

This invention relates to fuel injection pumps for internal combustion engines and more particularly internal combustion engines firing partially or wholly by the heat of compression and it is an object of this invention to provide an improved device of the type described in which the volume of fuel supplied to the engine cylinders is regulated by venting fuel from in front of the pump plungers throughout the compression stroke of the plunger and the device is of such construction that a single valve may serve to control the venting of fuel from in front of a plurality of pump plungers without the fuel being forced from in front of one plunger to in front of other plungers.

In the drawing—

Fig. 1 is a vertical sectional view of a fuel injection pump in accordance with this invention;

Fig. 2 is a partial vertical sectional view, drawn to a larger scale, of the control valve shown in the pump of Fig. 1;

Fig. 3 is a horizontal sectional view taken as on line 3—3 of Fig. 2; and

Fig. 4 is a partial vertical sectional view of a plunger of the pump shown in Fig. 1.

As shown in the drawing, a fuel injection pump constructed in accordance with this invention comprises a casing consisting of a substantially cylindrical portion 1 having a flange 2 at one end thereof by which it is secured to a correspondingly shaped flange 3 of a second casing portion 4. The casing portion 1 is also provided with an annular flange 5 which fits within an opening 6 of the casing portion 4. Screws 7 threaded into openings in the flange 3 secure the casing sections together. The casing section 1 is provided with a plurality of bores or cylindrical chambers 8, one for each of the cylinders of the engine with which the pump is to be used. The construction shown in the drawing is arranged for four of such chambers 8 placed with their axes spaced uniformly in a circle about the central axis of the cylindrical portion 1 of the casing. The bores 8 vary in diameter at different portions of their length and in each bore 8 there is a tubular plunger follower 10 which has one end thereof closed and which is slidably mounted in that portion of the bore 8 adjacent the casing portion 4 and held against turning by a pin 12 which engages in a slot 14 formed in the side wall of the plunger follower. In each bore 8 there is also fitted a fuel plunger bushing or cylinder 16 which extends into the follower 10 and is of greater diameter at one end so as to engage with

5 a shoulder 18 formed in the bore 8. The bushing 16 has a cylindrical opening or bore of uniform diameter throughout its length in which is slidably mounted the fuel plunger or piston 20. The plunger 20 at one end extends beyond the bushing 16 to engage the closed end of the follower 10 and its projecting end is provided with a spring seat 22 held in position by a spring wire 24 which engages in a groove 26 in the plunger. The spring seat 22 serves as a seat for a spring 28 which is confined between the spring seat and a shoulder formed in the bore 8 and which holds the end of the plunger 20 in engagement with the follower 10.

15 To operate the follower 10 and fuel plunger 20 the lower end of the follower 10 is recessed to receive a roller 30 mounted on a pin 32 which extends through a transverse opening in the follower 10 and is held in position by a spring wire 34 engaged in notches in the pin 32 and a groove in the follower 10. The roller 30 is positioned to be engaged by a cam 36 formed integral with a gear 38 on the end of a shaft 40 which is mounted in the casing portion 4 and arranged to be driven in suitable manner from the engine with which the pump is associated. The shaft 40 extends through a cylindrical boss 4a which is formed integral with the casing portion 4 and rotatably mounted in a bracket suitably supported from the engine. A set screw, threaded into the bracket and engaging in a groove 4b formed in the boss 4a secures the pump casing to the bracket and permits of rotative adjustment of the casing with respect to the bracket. 20 To provide for the free operation of the gear 38 and cam 36 the gear wheel is supported by a thrust bearing 42 and the shaft 40 is guided by a ball bearing 44, an oil seal 46 being provided between the bearings 44 and the face of the casing portion 4 in order to prevent leakage of the lubricant along the shaft 40.

25 Threaded into the bore 8 at the free end of the casing section 1 is a plug 48 which retains the plunger bushing 16 in its position in the bore 8 and which is provided with a central opening having a portion thereof shaped to provide a seat for the check valve 50. The plug 48 above the valve 50 is bored to receive a coupling member 52 having a central opening which communicates with a chamber above the valve 50 and is enlarged immediately above the valve 50 to receive a spring 54 which returns the check valve 50 to its seat. A second coupling member 56 cooperates with the coupling member 52 in securing the end of a pipe 58 which connects the

individual plunger bore to a cylinder of the motor with which the pump is associated.

At the axis of the casing portion 1 and equidistant from all of the plunger bores 8 is a bore having an inner portion forming a chamber 60 which is in communication through an opening 62 with a fuel container. Above the chamber 60 the bore is shouldered and has seated therein a plug 143 having a central bore 114. A screw threaded plug 66, also having a central bore, serves to secure the plug 143 in position and mounted in the bores of the plugs 66 and 143 and having threaded engagement with the plug 66 is a fuel supply controlling valve 75. Passage or ports 116 extend radially from the bore 114 of the plug 143 to the bores for all the pump plungers in the pump plunger bushings 16 and ports or passages 80 extend from the pump plunger bores to a chamber 118 which surrounds the plug 143 and which is in communication through port 120 with the source of fuel supply. The valve 75 is grooved, as at 140, and its inner end portion 141 of full diameter is shaped to provide a flat inclined surface 142^a on one side of the valve which cooperates with a shoulder in the bore 114 in controlling the passage of fuel through the bore 114 to the chamber 60. Controlling a port or passage common to all pump sections of the device prevents slight irregularities in the port sizes from affecting the amount of fuel supplied to the engine cylinders. In this construction the pump plungers 20 are grooved, as at 142 and 144, and have an axial port 84 extending from the upper ends of the plungers to transverse ports 146 and 148 communicating with the grooves 144 and 142, respectively.

In the operation of this device when a plunger 20 is retracted fuel is supplied through port 120, chamber 118 and port 80 to the pump plunger bore at the groove 144, then through the transverse port 146 and the axial port 84 to the chamber above the pump plunger. The port 148 and the groove 142 of the pump plunger are at this time closed by the bushing 16 and the upper end portion of the plunger, which is of full diameter, seals the port 116. As the plunger is raised the port 80 is cut off and communication between the groove 144 of the plunger and the bore for the valve 75 is established through the port 116 so that as fuel is forced from the chamber above the plunger 20 past the check valve 50 to an engine cylinder, fuel is also permitted to pass through the port 84 and port 146 to the port 116, past the inclined surface 142^a of the valve 75 and through the bore 114 to the fuel chamber 60 which is in communication through the port 62 with the fuel supply.

As a pump plunger is raised to its uppermost position communication is established between the groove 142 on the pump plunger and port 80 leading to the chamber 118 so that as the plunger attains its uppermost position the pressure above the plunger is vented through the port 84, port 148 and port 80 to chamber 118, releasing the pressure above the pump plunger and cutting off the supply of fuel to the engine cylinder. During the return movement of the plunger from its uppermost position some fuel may be supplied to the chamber above the plunger from the fuel supply chamber 118 through the port 80, port 148 and port 84 and also from the fuel chamber 60 past the valve 75 and through ports 116, 146 and 84. Port 80, however, is cut off very shortly after the return movement of

the plunger 20 starts and the port 116 is subsequently cut off and thereafter remains cut off, port 80 being reopened again upon movement of the plunger 20 to its lowermost position for the passage of fuel from the chamber 118.

In this construction it will be noted that the fuel control valve 75 does not control the supply of fuel to the bore for the pump plunger but controls a by-pass or waste passage which vents a portion of the fuel from the bore for the pump plunger as the pump plunger is operated to force the fuel to the engine cylinder, the valve 75 serving to control this discharge from the bore for each pump plunger. In this construction, 10 also, instead of having the pump plunger maintained at its uppermost position while each of the other pump plungers is operated the operating cam is so shaped that the pump plunger is returned to its lowermost position after each operation and remains in the lowermost position while each of the other pump plungers is operated. Thus, as each plunger 20 is on its delivery or outward stroke, the remaining plungers are positioned so that the ports 116 leading thereto are closed by the upper end portions of these plungers and the discharge of fuel except to the engine cylinder corresponding to the operating plunger or past valve 75 is prevented.

While the valve 75 has been shown and described as threaded into the plug 66 and manually adjustable it is to be understood that the valve 75 may be slidably mounted in the plug and controlled by a governor as shown in my co-pending application, Serial No. 48,744, filed Nov. 35 7, 1935, which resulted in Patent No. 2,166,876, issued July 18, 1939, and of which application this application is a division.

I claim—

1. In a fuel injection pump, a casing having a 40 plurality of pump plunger bores, a valve bore, a common discharge port and ports and passages connecting said bores, for supplying fuel to the pump plunger bores and for connecting said plunger bores to said common discharge port, 45 pump plungers in said plunger bores, means for operating said plungers to force fuel to individual engine cylinders and a valve in said valve bore controlling said common discharge port for venting fuel from in front of all plungers during 50 the pumping strokes thereof, said plungers having intermediate portions closing the fuel supply ports during the pumping strokes of said plungers and end portions closing the ports to said discharge valve in the retracted positions of said 55 plungers and said plunger operating means positioning each plunger in retracted position after an operation thereof prior to the operation of the succeeding plunger.

2. In a fuel injection pump, a casing having a 60 plurality of pump plunger bores, a valve bore, a common discharge port and ports and passages connecting said bores, for supplying fuel to the pump plunger bores and for connecting said plunger bores to said common discharge port, 65 pump plungers in said plunger bores, means for operating said plungers to force fuel to individual engine cylinders and a valve in said valve bore controlling said common discharge port for venting fuel from in front of all plungers during the pumping strokes thereof, said plungers having intermediate portions closing their fuel supply ports during their pumping strokes and opening said fuel supply ports to stop fuel injection and end portions closing the ports to said discharge valve in the retracted positions of said plungers,

and said plunger operating means positioning each plunger in retracted position after an operation thereof prior to the operation of the succeeding plunger.

3. In a fuel injection pump, a casing having a plurality of pump plunger bores, a valve bore, a common discharge port and ports and passages connecting said bores, for supplying fuel to the pump plunger bores and for connecting said plunger bores to said common discharge port, pump plungers in said plunger bores, means for operating said plungers to force fuel to individual engine cylinders and a valve in said valve bore controlling a common discharge port for venting fuel from in front of all plungers during the pumping strokes thereof, said plungers having portions controlling the supply of fuel to said plunger bores and the termination of fuel injection and being extended to close the ports leading to said discharge valve in the retracted positions of said plungers, and said plunger operating means positioning each plunger in retracted position after an operation thereof prior to the operation of the succeeding plunger.

4. In a fuel injection pump having a plurality of pump plunger bores, a valve bore, a common discharge port and passages for the supply of fuel to said plunger bores and the discharge of fuel from said plunger bores to individual cylinders of an engine, pump plungers in said plunger bores for forcing fuel from said bores to the corresponding engine cylinders, means for operating said plungers, means for venting fuel from in front of said plungers to said common discharge port, a valve in said valve bore controlling the venting of fuel through said common discharge port from in front of all plungers during the pumping strokes thereof and means for preventing flow to said plunger bores by said plungers.

5. In a fuel injection pump having a plurality of pump plunger bores, a valve bore, a common discharge port and passages for the supply of fuel to said plunger bores and the discharge of fuel from said plunger bores to individual cylinders of an engine, pump plungers in said plunger bores for forcing fuel from said bores to the corresponding engine cylinders, means for operating said plungers, means for venting fuel from in front of said plungers to said common discharge port, a valve in said valve bore controlling the venting of fuel through said common discharge port from in front of all plungers during the pumping strokes thereof and means for preventing flow of fuel from in front of one plunger to in front of another plunger by said second plunger.

6. In a fuel injection pump having a plurality of pump plunger bores, a valve bore, a common discharge port and passages for the supply of fuel to said plunger bores and the discharge of fuel from said plunger bores to individual cylinders of an engine, pump plungers in said plunger bores for forcing fuel from said bores to the corresponding engine cylinders, means for operating said plungers, means for venting fuel from in front of said plungers to said common discharge port, a valve in said valve bore controlling the venting of fuel through said common discharge port from in front of all plungers during the pumping strokes thereof and means on said plungers for preventing flow of fuel from in front of one plunger to in front of another plunger.

7. In a fuel injection pump having a plurality of pump plunger bores, a valve bore, a common

discharge port and passages for the supply of fuel to said plunger bores and the discharge of fuel from said plunger bores to individual cylinders of an engine, pump plungers in said plunger bores for forcing fuel from said bores to the corresponding engine cylinders, means for operating said plungers, means for venting fuel from in front of said plungers to said common discharge port, a valve in said valve bore controlling the venting of fuel through said common discharge port from in front of all plungers during the pumping strokes thereof and means on each plunger for preventing flow of fuel to in front of said plunger from in front of all other plungers.

8. In a fuel injection pump a casing having a plurality of pump plunger bores, a valve bore, a common discharge port and ports and passages connecting said valve and plunger bores and for the passage of fuel to said plunger bores and from said plunger bores to individual engine cylinders, pump plungers in said plunger bores, means for operating said plungers to force fuel to said individual engine cylinders, means for venting fuel from in front of said plungers to said common discharge port and a valve controlling the venting of fuel through said common discharge port from in front of all plungers during the pumping strokes thereof and means on each plunger effective when said plunger is inoperative to prevent flow of fuel from said valve bore to said plunger bore.

9. In a fuel injection pump, a casing having a plurality of pump plunger bores, a valve bore, a common discharge port and ports and passages connecting said valve and plunger bores and for the passage of fuel to said plunger bores and from said plunger bores to individual engine cylinders, pump plungers in said plunger bores, means for operating said plungers to force fuel to said individual engine cylinders, means for venting fuel from in front of said plungers to said common discharge port and a valve controlling the venting of fuel through said common discharge port from in front of all plungers during the pumping strokes thereof, said plungers having portions closing the passages from said plunger bores to said valve bore in the retracted position of said plungers to prevent flow of fuel from said valve bore to said plunger bores.

10. In a fuel injection pump a casing having a plurality of pump plunger bores, a valve bore, a common discharge port and ports and passages connecting said valve and plunger bores and for the passage of fuel to said plunger bores and from said plunger bores to individual engine cylinders, pump plungers in said plunger bores, means for operating said plungers to force fuel to said individual engine cylinders, means for venting fuel from in front of said plungers to said common discharge port and a valve controlling the venting of fuel through said common discharge port from in front of all plungers during the pumping strokes thereof, said plungers having ports for venting fuel from in front of said plungers to stop the flow of fuel to the engine cylinders and end portions effective in the retracted position of said plungers to prevent flow of fuel to the bores of inactive plungers from the bore of an operating plunger.

11. In a fuel injection pump having a plurality of pump plunger bores, a valve bore, a common discharge port and passages for the supply of fuel to said plunger bores and the discharge of

fuel from said plunger bores to individual cylinders of an engine pump, plungers in said plunger bores for forcing fuel from said bores to the corresponding engine cylinders, means for operating said plungers, said means operating each plunger individually and leaving the remaining plungers in the retracted position, means for venting fuel from in front of each plunger during the operating stroke thereof to said common discharge port and a valve controlling said port, said plungers preventing flow of fuel from in front of an operating plunger to in front of the remaining plungers.

12. In a fuel injection pump a casing having a plurality of pump plunger bores, a valve bore, 15 a common discharge port and fuel ports and pas-

sages therein, pump plungers in said plunger bores, means for operating said plungers to force fuel through said ports and passages to individual engine cylinders and to said common discharge port and a valve in said valve bore controlling the common discharge port for venting fuel from in front of all plungers during the pumping strokes thereof, said plungers having formations for controlling said ports and passages in said casing and in their retracted positions preventing flow of fuel from said valve bore to said plunger bores and opening passages for the flow of fuel from a fuel supply to said plunger bores.

EVERETT M. PURDY.
